UNITED STATES PATENT OFFICE

PAUL GERARD, OF LAUREL, MONTANA

VALVE ACTUATING MECHANISM FOR INTERNAL COMBUSTION ENGINES

Application filed October 22, 1929. Serial No. 401,459.

This invention relates to improvements in actuating mechanism for valves of internal combustion engines and has for its primary object to provide a mechanism whereby a smoother opening and closing of a valve may be effected than in present systems and whereby also adjustment of the mechanism may be easily made to increase or decrease the amount of movement of the valve in association with which it is employed.

Another object of the invention is to provide a mechanism for actuating valves of internal combustion engines which is of simple construction and so designed that adjustments may be made thereto while the engine is operating to obtain the best results through the actuation of the valves.

Other objects and advantages of the invention will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view partly in side elevation and partly in section of one of the valve operating units embodying the present invention.

Figure 2 is a view in top plan of the structure shown in Figure 1.

Figure 3 is a sectional view taken upon the line 3-3 of Figure 1.

Figure 4 is a plan view of the valve stem engaging lever with the cap removed.

Referring more particularly to the drawings wherein like numerals of reference indicate corresponding parts throughout the several views, the numeral 1 indicates generally the head of an internal combustion engine showing the application thereto of the valve actuating mechanism embodying the present invention.

The present mechanism is designed for the operation of the overhead type of valve and as shown is supported by a series of arbors 2 which are mounted upon and formed integral with the engine head, there being one of these arbors for each of the valves to be operated by the mechanism. Each of the arbors 2 comprises a base portion 3 and a forwardly curved arm 4 through which is formed a downwardly extending threaded opening 5 designed to receive an adjusting screw 6 which is maintained in the desired position by a lock nut 7 engaging thereabout and bearing upon the top of the arm 4.

Directly in alignment with each arbor 2 transversely of the engine there extends upwardly through the engine head a valve stem 8 which is normally urged upwardly in the usual manner by a coiled spring 9 surrounding it and bearing against a transversely extending pin 10 passing therethrough.

The inner face of each of the arbors 2 is formed in the base portion thereof to provide a bearing cradle 11 and seated in this cradle is the bearing or hinge knuckle 12 which forms an integral part of the actuating lever for the adjacent valve, indicated generally by the numeral 13.

Each of the actuating levers 13 comprises an elongated flat body from one end of which the knuckle 12 extends, the body tapering toward the other end to form the finger 14 which, when the knuckle is in a bearing cradle 11, overlies the adjacent valve stem 8 in the manner shown. This finger has a threaded passage formed therethrough for the reception of the adjusting screw 15 which, when the mechanism is actuated, engages the upper end of the valve stem to actuate the same. A suitable locking nut 16 is used in association with the adjusting screw 15 to maintain the same in set position.

Intermediate its ends each of the actuation levers has formed in the upper edge the semi-circular recess 17, the face of which is formed or cut away to provide the track groove 18 in the lower portion of which is formed a cam lug 19 each of the faces of which gradually slope off as indicated at 20 to merge with the 100

face of the inner wall of the groove 18 as shown.

Extending longitudinally of the engine head is a hinge rod 21 which passes through each of the actuating lever knuckles 12 and separating the hinge rod from each of the knuckles is a suitable bushing 22. An oil groove 23 is formed from the track groove 18 of each of the actuating levers to and through the adjacent bushing 22 so that oil may pass from the groove 18 to the bushing to lubricate the same.

Secured to the top edge of each actuating lever 13 is an oil retaining cap 24. Each of these caps is formed to provide a semi-circular recess 25. The radial center of which is slightly above the radial center of the recess 17 in the underlying lever. The inner face of the recess 25 of each of the caps is cut away enough to clear the rotating roller 35 slightly more than the distance of the height of the cam lug 19, and forming the groove 26 which aligns at its ends with the groove 18 in the lever in the manner shown. At each end each 25 of the caps has a laterally projecting ear 27 through which a securing screw 28 is passed for engagement in the body of the supporting lever and to prevent the removal of the cap.

The top of the cap 24 has a depression 29 formed therein and formed radially through this part of the cap from the depression to and opening into the groove 26 is an oil passage 30. The depression 29 is aligned with the adjusting screw 6 and the lower end of the 35 same is adapted to engage therein for making necessary vertical adjustments of the valve actuator.

The valve levers 13 are each normally urged upwardly by a coiled spring 31 the lower end 40 of which engages over a projection 32 formed upon the body of the engine head under the lever while the upper end engages a similar projection 33 formed upon the lower side or edge of the lever 13. It will thus be seen that 45 the lever 13 and cap therefor will be normally forced upwardly by the spring 31 so as to maintain constant engagement between the set screw 6 and the top of the cap 24.

Extending longitudinally of the engine 50 head or top 1 is a cam shaft 34, this shaft extending through the coating recesses of the aligned levers and caps and having its longitudinal center substantially in the same horizontal plane as the radial center of the recesses 17 of the levers, but free from engagement with the edges of the recesses.

Spaced at suitable intervals longitudinally of and also circumferentially of the cam shaft 34 are cam rollers 35 each of which is 60 snugly received in the grooves 18 and 26 of a lever and its associate cap. Each of these rollers is preferably held in place in the pocket 36 in which it is positioned, by a pin 37 which extends longitudinally of the shaft and is inserted to position from a re-

cess 38 arranged at one side of the roller recess or pocket as shown.

Any suitable means may be employed for supporting the cam shaft 34 so that it will be free from contact with the lever bodies 70 and their caps, the rollers only engaging the levers at the period which will be hereinafter described.

The cam shaft 34 has extending longitudinally therethrough an oil passage 39 which 75 communicates by means of lateral passages 40 with each of the cam roller recesses or pockets 36 so that oil forced into this passage or bore 39 may be distributed into each of the cam rollers and will then flow from the 80 same into the guide grooves in which it works, some of the oil being forced therefrom upwardly through the passage 30 to work out into the depression 29 into which the set screw 6 engages and some passing through the oil 85 groove 23 to lubricate the bearing bushing 22.

In operation the set screw 6 is arranged so that rotating roller 35 is in desired position or desired relation to cam lug 19. The setting of screw 15 is then made so that each lever 13 is in slightly spaced relation with respect to the end of adjacent valve stem 8 so the expansion of the entire valve through the influence of heat will be permitted without causing the valve seat to be held open.

The rotating lever will lightly engage the inner wall of groove 18 of the lever with spring pressure against it and holding roller and inner wall tight together so that when the cam shaft is rotated the cam roller will ride smoothly onto the inclined surface 20 between the inner wall of the groove and the cam lug 19 to smoothly swing the lever down for contact of the screw 15 with the valve stem.

The roller will then come into contact with the lug 19 and sharply force the lever down for the opening of the valve adjacent thereto. Adjustment of the cam levers for governing the amount of movement of the valves is effected by actuation of the screw 6, the slight movement of the valve being obtained by moving the screw down so as to depress the lever slightly to move the lug 19 away from the cam roller. Increased movement of the 115 valve is brought about by shifting the screw 6 in the opposite direction so that contact of the roller with the bottom wall of the groove 18 will occur soon after the roller passes the horizontal center of the groove thus applying downward pressure to the lever sooner than would be the case if the set screw 6 were moved downwardly as previously described.

From the foregoing description it will be readily seen that with this valve actuating 125 mechanism of the character herein described controlling the operation of the valves of an internal combustion engine extremely fine adjustments may be made to bring about the opening or closing of the valves at the desired 130

periods and further these adjustments may be made during the running of the engine so that the immediate effects resulting from the adjustments can be seen.

5. The construction of the mechanism of the present invention is such that there is very little wear upon the elements employed so that the life of the mechanism will be long.

As will be readily seen the present valve actuating mechanism may be so adjusted that the particular valve which it is set to control may be completely thrown out of operation if such procedure is found necessary. Due to the fact that the height of the cam lug 19 is less than the distance between the roller 35 and the bottom of the groove 26 of the cap when the roller is in position therein this throwing out of operation of a valve is accomplished by raising the screw 15 and shifting downwardly the screw 6 so as to force the arm 13 down to the point where the roller will pass freely over the lug 19. From this it will also be apparent that adjustment can be made of the mechanism whereby the roller 35 may be made to strike the lug 19 low down or near its tip in order to govern the downward swing of the arm and consequent operation of the valve stem 8.

Having thus described my invention, what

30 I claim is:—

1. A valve actuating mechanism comprising a lever, means for pivotally mounting the same adjacent a valve, means for effecting operative engagement between the lever and said valve, resilient means normally urging said lever away from the valve, a shaft extending transversely of the lever, a cam carried by the shaft, a collar carried by the lever and surrounding said shaft and the cam, and a cam follower forming a part of said collar and adapted to be engaged by said cam.

2. A valve actuating mechanism comprising a lever, means for pivotally mounting the same adjacent a valve, means for effecting operative engagement between the lever and said valve, resilient means normally urging said lever away from the valve, a shaft extending transversely of the lever, a cam carried by the shaft, a collar carried by the lever and surrounding said shaft and the cam, a cam follower forming a part of said collar and adapted to be engaged by said follower, and means for vertically adjusting said collar and lever for controlling the stroke of the lever.

3. A valve actuating mechanism comprising a lever pivotally mounted at one end and having its other end arranged for contact with a valve stem, said lever having a recess formed therein and further having a groove formed along the inner face of the recess, a cam follower formed in said groove, a cam shaft extending transversely of the lever and passing through said recess, a cam carried by the shaft adapted to work in said groove,

and resilient means normally urging said lever upwardly.

4. A valve actuation mechanism comprising a lever pivotally mounted at one end and having its other end arranged for contact with a valve stem, said lever having a recess formed therein and further having a groove formed along the inner face of the recess, a cam follower formed in said groove, a cam shaft extending transversely of the lever and passing through said recess, a cam carried by the shaft adapted to work in said groove, resilient means normally urging said lever upwardly, a cap covering said recess and grooved to receive said cam, and adjusting means engaging said cap for shifting the same and the lever in opposition to said resilient means.

5. A valve actuating mechanism comprising a support designed to form a part of an engine head and including an arm, a lever swingingly connected with said support and having one end arranged for engagement with a valve stem, said lever having a semi-circular recess formed therein and further having the wall of said recess provided with a groove, a cam lug formed in said groove at the lowermost point thereof, a cap adapted to be secured over said recess and having a grooved recess formed therein coinciding with the groove in the lever, a cam shaft extending through the opening formed by said coinciding recesses, a cam roller carried by the shaft and working in said grooves for engagement with said lug, and means carried by said arm for vertically adjusting the arm.

6. A valve actuating mechanism comprising a support designed to form a part of an engine head and including an arm, a lever swingingly connected with said support and having one end arranged for engagement with a valve stem, said lever having a semi-circular recess formed therein and further having the wall of said recess provided with a groove, a cam lug formed in said groove at the lowermost point thereof, a cap adapted to be secured over said recess and having a grooved recess formed therein coinciding with the groove in the lever, a cam shaft extending through the opening formed by said coinciding recesses, a cam roller carried by the shaft and working in said grooves for engagement with said lug, means carried by said arm for vertically adjusting the arm, and means carried by the arm for regulating the period of movement thereof before actuation of the adjacent valve is effected.

7. A valve actuating mechanism comprising a support designed to form a part of an engine head and including an arm, a lever swingingly connected with said support and having one end arranged for engagement with a valve stem, said lever having a semi-circular recess formed therein and further having the wall of said recess provided with

a groove, a cam lug formed in said groove at the lowermost point thereof, a cap adapted to be secured over said recess and having a grooved recess formed therein coinciding with the groove in the lever, a cam shaft extending through the opening formed by said coinciding recesses, a cam roller carried by the shaft and working in said grooves for engagement with said lug, means carried by said arm for vertically adjusting the arm, and a spring member arranged beneath the lever and normally urging the same upwardly against the action of said adjusting means.

8. In a valve actuating mechanism for internal combustion engines, including a valve having a stem projecting upwardly of the engine body, an elongated member pivotally mounted at one end and having its other end arranged for engagement with said valve stem to actuate the same, resilient means normally urging said member to swing upwardly, means for limiting the upward movement of the member, said member being formed to provide a substantially elliptical recess, a shaft extending transversely through said recess, said recess having a groove formed about the inner face thereof, a cam roller carried by the shaft and adapted to position in said groove, and a cam body formed upon the lower wall of the groove in the lower part of the recess for contact with said roller.

9. In a valve actuating mechanism for internal combustion engines, including a valve having a stem projecting upwardly of the engine body, an elongated member pivotally mounted at one end and having its other end arranged for engagement with said valve stem to actuate the same, resilient means normally urging said member to swing upwardly, means for limiting the upward movement of the member, said member being formed to provide a substantially elliptical recess, a shaft extending transversely through said recess, said recess having a groove formed about the inner face thereof, a cam roller carried by the shaft and adapted to position in said groove, a cam body formed upon the lower wall of the groove in the lower part of the recess for contact with said roller, and means for introducing oil into the groove to provide an oil cushion therein for said roller.

10. In a valve actuating mechanism for internal combustion engines, including a valve having a stem projecting upwardly of the engine body, an elongated member pivotally mounted at one end and having its other end arranged for engagement with said valve stem to actuate the same, resilient means normally urging said member to swing upwardly, means for limiting the upward movement of the member, said member being formed to provide a substantially elliptical recess, a shaft extending transversely through said recess, said recess having a groove formed about

the inner face thereof, a cam roller carried by the shaft and adapted to position in said groove, a cam body formed upon the lower wall of the groove in the lower part of the recess for contact with said roller, said cam roller being mounted in a recess in said shaft, and means for supplying oil to the cam roller and to said groove comprising an oil passage formed through the shaft and opening into the recess receiving the cam roller for discharge of oil thereinto and into said groove.

11. A valve actuating mechanism, comprising a pivotally mounted lever, means for effecting a working engagement between the lever and a valve body, a cam carried by said lever, a cam roller arranged to engage said cam, and resilient means normally urging said lever to move in opposition to the movement imparted thereto by the roller.

12. A valve actuating mechanism, comprising a lever arm pivotally mounted at one end adjacent a valve body, adjustable means carried by said arm at its other end for engaging said valve body, a cam formed upon said arm, a cam roller arranged to rotate above said arm and to contact with said cam for depressing the arm, and resilient means normally urging said arm to move upwardly.

13. A valve actuating mechanism, comprising a lever arm pivotally mounted at one end adjacent a valve body, adjustable means carried by said arm at its other end for engaging said valve body, a cam formed upon said arm, a cam roller arranged to rotate above said arm and to contact with said cam for depressing the arm, resilient means normally urging said arm to move upwardly, an arm extending above said first mentioned arm, and means carried by the last mentioned arm for engaging and holding the first mentioned arm in a predetermined position.

In testimony whereof I hereunto affix my signature.

PAUL GERARD.
